PUMP FOR THE ELEVATION OF LIQUIDS

Leo Maximilian Bradaska, Cordoba City, Argentina

Application February 26, 1958, Serial No. 717,766

1 Claim. (Cl. 103—260)

The present invention is related to pumps in general and, more particularly, to a new pump for raising liquids such as, for instance, water, hydrocarbons and such like which have to be lifted by force from underground layers to the surface. This new pump is specially designed to serve for draining oil wells which having lost their excess pressure gases, have been deprived of their lifting energy, with the consequent advantage that due to this new pump a better and practically total working of any oil well can be obtained even though its automatic purge has ceased. It is redundant to enlarge upon the great advantage of this new pump which allows of a larger rentability of oil wells and a higher index of productivity, inasmuch as all the oil wells which, in the course of years, had to be abandoned due to having lost their capacity of raising the oil will be made productive due to the raising power of the new pump. If up to the present only liquid hydrocarbons have been referred to, it should now be stressed that the new pump can be used as well for the raising to the surface of other liquids such as water and such like, thus providing yet another means for extracting liquids from layers situated in the subsoil.

Other objects and advantages will become apparent in the following specification when considered in light of the attached drawings, in which:

Figure 1 is a fragmentary view of a transversal vertical cut through the new pump set up for raising liquids.

Figure 2 is a horizontal transversal cut through the pump of Figure 1 following line II—II of the figure; and

Figure 3 is a horizontal transversal cut through the pump of Figure 1 following line III—III of the figure.

With reference now to the accompanying drawings, it is to be pointed out that the new pump 1 for lifting liquids has an outer jacket 2 having a closed lower end portion 2a which may be plunged into the layer of liquid to be lifted, while the open upper end 2b of the outer jacket 2 is hermetically closed by means of a ring-shaped lid 3. A concentric pipe 5 extends through the lid 3 concentric with the jacket 2 and is provided with a lower outlet 6 shaped like a truncated cone and having diametrical choke 7 in operative engagement spaced above and coaxially with the truncated cone shaped head 8 of a nozzle 9 having an axial passage 10. The bottom 11 of the jacket 2 is integral therewith and shaped like an inverted funnel. The lid 3 of the jacket 2 has injection nozzles 12 extending therethrough and connected by a piping 17 to at least one device (not shown) generating forced gas as, for instance, steam, compressed air and the like.

The nozzle 9 at the lower portion of the jacket 2, has in addition to its head 8 in the shape of a truncated cone, a ring-formed lip 13 acting as seat and a hermetic retention means for the nozzle 9 in the outlet 14 of the bottom 11. The nozzle 9 extends through the outlet 14 with the ring lip 13 engaging the upper inner end of the bottom 11. A securing means 16 is mounted on the nozzle 9 and locks the nozzle 9 against the lower side 15 of the bottom 11.

2

zle 9 and locks the nozzle 9 against the lower side 15 of the bottom 11.

The injection nozzles 12 open into the interior of a ring-shaped chamber defined by the outer periphery of the lifting pipe 5 on one side and the inner periphery of the jacket 2 on the other, and are connected to the piping 17 coming from the forced gas generating source (not shown), by means of an interposed preferably ring-shaped collector 18, acting as compensator and stabilizer for the entering forced gas column, particularly in those cases where a plurality of injection nozzles 12 are provided.

The pipe 5 may be provided beyond the lid 3 of the outer jacket 2 with tubular prolongation means 19 for transporting the extracted liquid to the storing place (not shown).

When the pump 1 is set up in a perforation 20 made in the subsoil 21 and the lower portion 2a of the jacket 2 is plunged into the layer of liquid 22 to be lifted, the connections are completed at one end of the piping 17 with a forced gas generating source, while the raising pipe 5 is coupled on to the storing place for the extracted liquid.

When the valves (not shown) of the piping 17 are opened, a ring-shaped column of gas, for instance, steam, compressed air etc. having a suitable atmospheric excess pressure is injected through the collector 18 and the nozzles 12 into the ring-shaped chamber 4 along which it flows down to the lower portion of the chamber 4 where it rebounds from the adjacent face formed like a truncated cone of the bottom 11 shaped like an inverted funnel to be deflected, following the bent arrows, in ascending direction, crossing the reduced zone defined by the head 8 of the nozzle 9. The air then flows through the complementary outlet 6 in the pipe 5 to follow its ascending path through the passage 23 of the pipe 5.

When this forced ascending gas column passes through the above described reduced zone, a vacuum is created within the passage 10 of the spout or nozzle 9 which absorbs the liquid from the layer 22, which spouts in the form of a jet through the outlet of the nozzle 9 into the passage 23 of the pipe 5 passing through the throttle 7 of the same, the extracted liquid being sucked by the ascending forced gas column and finally discharged through the prolongation or prolongations 19 into the storage place or places, where the liquid is eventually separated from the carrier gas.

The quantity of liquid which is raised is regulated by the speed and atmospheric excess pressure of the gas within the passage 10, the atmospheric excess pressure being taken into account however, the depth of the well and other factors well known to the experts.

It can be appreciated in view of the foregoing description that the structure of the device, which it is desired to protect, is extremely simple and totally lacking in movable or rotative pieces, which feature increases considerably the duration of its components. It must be pointed out, furthermore, that the relative price of the new pump is extremely low as compared with the profits yielded by its usefulness, apart from the fact that, with the aid of the new pump, considerable quantities of liquid can be extracted from oil wells which have lost their lifting gas, and which, up to the present, could not be made profitable, the said properties giving singular importance from every point of view to the new construction.

It is to be understood that the new pump which it is desired to protect is susceptible of certain modifications of detail and structure provided they fall within the spirit and scope of the same as defined in the appended claim.

What I claim is:

A jet pump comprising a cylindrical hollow jacket, an upwardly and inwardly converging frusto-conical bottom wall integrally formed on the lower end of said jacket,

said bottom wall having an axial bore formed therein, a lid secured in sealed relation to the upper end of said jacket, a pipe mounted concentrically in said jacket and extending in sealed relation through said lid, an integral choke formed on the lower end of said pipe, said choke having an upwardly and inwardly converging frusto-conical axial wall terminating in an axial port having a diameter substantially smaller than the diameter of said pipe, said pipe having the lower end thereof spaced substantially above said bottom wall, a hollow cylindrical nozzle, an annular lip integrally formed on said nozzle and extending radially outwardly therefrom intermediate the upper and lower ends thereof, said nozzle having the lower end thereof extending downwardly through said axial bore in said bottom wall with said lip in engagement with said bottom wall, means releasably mounted on the lower end of said nozzle in engagement with the lower face of said bottom wall securing said nozzle to said bottom wall, a frusto-conical head with an upwardly and inwardly converging outer wall integrally formed on

10

15

20

the upper end of said nozzle, said head having the upper end thereof spaced slightly below the lower end of said pipe and a plurality of gas injection nozzles mounted in said lid and arranged to direct gas under pressure into the space between said jacket and said pipe whereby said gas flowing from the space between said jacket and said pipe through said choke in the lower end of said pipe draws fluid material through said nozzle and through said choke into said pipe.
